[57] **CLAIM**

The ornamental design for the food carton, as shown and described.

DESCRIPTION

FIG. 1 is an isometric view of a food carton embodying my new design;

FIG. 2 is a side elevational view thereof;

FIG. 3 is a bottom plan view, the dash lines representing fold lines;

FIG. 4 is an elevational view showing the end not seen in FIG. 1.

FIG. 5 is a top plan view thereof;

FIG. 6 is a developed plan view of the carton;

FIG. 7 is a side view thereof; and

FIG. 8 is an end view thereof.

FIG. 1.

FIG. 2.

FIG. 3.

FIG. 4.

FIG. 5.
